(57) **CLAIM**

The ornamental design for a vanity mirror, as shown and described.

DESCRIPTION

FIG. 1 is a perspective view of a vanity mirror design showing my new design.

FIG. 2 is a front view of a vanity mirror.

FIG. 3 is a rear view of a vanity mirror.

FIG. 4 is a left side view of a vanity mirror.

FIG. 5 is a right side view of a vanity mirror.

FIG. 6 is a top view of a vanity mirror.

FIG. 7 is a bottom view of a vanity mirror; and,

FIG. 8 is a rear side perspective view of a vanity mirror. The broken lines in the drawings depict portions of the vanity mirror that form no part of the claimed design.
